ATTORNEY

UNITED STATES PATENT OFFICE.

MANETHO C. JACKSON, OF DENVER, COLORADO.

BALING-PRESS.

SPECIFICATION forming part of Letters Patent No. 367,106, dated July 26, 1887.

Application filed April 29, 1887. Serial No. 236,562. (No model.)

To all whom it may concern:

Be it known that I, MANETHO C. JACKSON, a citizen of Denver, residing at Denver, in the county of Arapahoe and State of Colorado, have invented certain new and useful Improvements in Horse-Powers for Baling-Presses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to horse-powers for baling-presses, and the objects of my invention are, first, to provide a horse-power for baling-presses by which a positive double reciprocating action will be imparted to the 20 plunger of a baling-press while the power-sweep is performing a revolution; second, to provide a strong, effective, and inexpensive horse power for operating baling-presses, that can be easily mounted on wheels for transportation. I accomplish these objects by the 25 mechanism illustrated in the accompanying drawings, in which—

Figure 1 is a side view of the entire machine with one side of the frame removed and 30 the cross-pieces in section. Fig. 2 is a top view of the same with the upper cross-timber of the frame broken away in order to show the mechanism below it.

Similar letters refer to similar parts throughout the several views.

35 In the drawings, A represents the frame by which the operating parts of the device are supported.

B is a double cam formed as shown, and is 40 held in position by an upright shaft, C, which is provided with a square projection, C', on its upper end. The lower end is formed with a shoulder, on which it rests. It is held in position and rotates in bearings D and D', which 45 are firmly attached to the main frame. The sweep E, to which the power is applied, is provided with a square socket, which fits over the square projection C' on the upper end of

the shaft C. The arm G is formed, as shown, and is pivoted to the frame A by the bolt F. 50 This arm is provided with a friction-wheel, H, held in position by the bolt I, against which the face of the cam B operates. One end of the rods J and K are pivoted to the arm G by the bolt I. The cam L, with its arm L', (which 55 is pivoted to the rod K by the bolt K'), is pivoted to the frame by the bolt L'. The rod M is pivoted to the rod J by the bolt N at one end. The opposite end is formed into an eye, by which it is connected to the plunger. This 60 rod is held in position by the guide-boxes O and P, which are attached to the frame. On the sides of the frame are attached the axles R, on which wheels may be placed for the purpose of transferring the machine from place 65 to place.

In operating, the power is applied to the sweep E, which rotates the cam B, which forces the arms G K L', cam L, and rods M and J from the position shown in dotted lines 70 to the position indicated in the solid lines, and as the cam B continues in its course it comes in contact with the cam L and turns it to one side, as shown in dotted lines, which brings the mechanism back to its normal position. Thus it will be seen that each arm of the cam as it makes a revolution causes the rod M to move back and forth, which gives a 75 double reciprocating movement of the rod M with each revolution of the sweep. 80

Having now fully described my invention, what I claim as new, and desire to secure by Letters Patent, is—

In a horse-power for operating baling-presses, the combination of the connecting- 85 rods M and J, arm G, friction-wheel H, cam L, rod L', rod K, cam B, shaft C, and sweep E, and frame A, substantially as described, and for the purpose set forth.

In testimony whereof I affix my signature in 90 presence of two witnesses.

MANETHO C. JACKSON.

Witnesses:

JOHN CARSON,
P. P. GAYLORD.
